DESIGN FOR A DISPLAY STAND

John A. Kern, Chicago, Ill., assignor to The W. J.
McCahan Sugar Refining & Molasses Co.,
Philadelphia, Pa., a corporation of Delaware

Application September 13, 1937, Serial No. 71,588

Term of patent 14 years

To all whom it may concern:

Be it known that I, John A. Kern, a citizen of the United States, residing at Chicago, in the county of Cook and State of Illinois, have invented a new, original, and ornamental Design for a Display Stand, of which the following is a specification, reference being had to the accompanying drawing, forming a part thereof.

In the drawing:

Fig. 2 is a side elevation thereof; and

Fig. 3 is a top plan view.

I claim:

The ornamental design for a display stand, as shown.

JOHN A. KERN.
